UNITED STATES PATENT OFFICE.

FRIDOLIN AUGUSTINE BUHOLZER, OF TORONTO, ONTARIO, CANADA.

DESIGN FOR A PERFUME-VIAL.

41,299.

Specification for Design.

Patented Apr. 11, 1911.

Application filed November 21, 1910. Serial No. 593,589. Term of patent 7 years.

To all whom it may concern:

Be it known that I, FRIDOLIN AUGUSTINE BUHOLZER, a citizen of the Republic of Switzerland, and residing in the city of Toronto, county of York, Province of Ontario, in the Dominion of Canada, have invented a new, original, and ornamental Design for Perfume-Vials, of which the following is a specification, reference being had to the accompanying drawing, forming part of the same.

The drawing shows a perspective view of the vial and in the said drawing 1 is the body portion having the oval shaped ends 2 and 5 the latter being the cap.

9 is an ornamental and fanciful design on the outer surface of the body portion 1, said design consisting of a diagonal mesh with intersecting horizontal rings and extending all around said body portion.

I claim,

The ornamental design for a perfume vial as shown and described.

Signed at the city of Toronto, county of York, Province of Ontario, in the Dominion of Canada, this 17th day of November, 1910.

FRIDOLIN AUGUSTINE BUHOLZER.
